UNITED STATES PATENT OFFICE.

ALPHONZO LE ROY, OF DUNKIRK, AND BENJAMIN MARTIGNONI, OF WESTFIELD, NEW YORK; SAID MARTIGNONI ASSIGNOR TO GALEN B. EVERTS, OF DUNKIRK, NEW YORK.

ADDRESSING-MACHINE.

SPECIFICATION forming part of Letters Patent No. 325,945, dated September 8, 1885.

Application filed March 23, 1885. (No model.)

To all whom it may concern:

Be it known that we, ALPHONZO LE ROY, of Dunkirk, and BENJAMIN MARTIGNONI, of Westfield, in the county of Chautauqua and 5 State of New York, have invented certain new and useful Improvements in Addressing-Machines, of which the following is a specification.

Our invention relates to addressing-machines of that class in which the addresses are cut from a continuous printed strip and pasted to the paper wrapper or other article.

In the drawings, Figure 1 is a perspective view of our improved machine; Fig. 2, a top plan view of the same. Fig. 3 is a vertical longitudinal central section; Fig. 4, a horizontal section on the line $x-x$ of Fig. 3; Figs. 5 and 6, views illustrating the paper-feeding mechanism.

20 The objects of our invention are to render positive the feeding of the printed address-strip, to gum the latter evenly, and to vary the amount or degree of feed to suit different width addresses.

25 The invention also consists in various features and details of construction, hereinafter set forth.

A indicates the base-block of our machine, upon which are mounted the upright side 30 frames, $a-a$, which may be of any desired form or configuration and of any suitable material.

Between the uprights $a-a$ is a box or receptacle, B, containing glue, gum, paste, or any 35 other suitable material for coating the printed address-strip, as is usual, the rear end of said box being higher than its forward end, as shown in Fig. 2.

Within and extending transversely across 40 the box B is a large roller, C, provided with trunnions $b-b$ at each end, said trunnions working in boxes in the uprights $a-a$, as shown in Fig. 1, the uprights being slotted vertically to allow the roller C to be removed 45 readily. Hooks c , pivoted on the side frame, engage over the trunnions b and hold them to their seats. On one side of the machine the journal of the roller C is extended out-

ward through the frame and provided with a ratchet-wheel, D, as shown in Fig. 1. 50

The box or receptacle B carries at its forward end a small roller, E, as shown in Figs. 1 and 2, while a similar roller, F, extends between the uprights $a-a$, parallel with and a short distance in advance of the roller E, as 55 shown in Figs. 2 and 3.

G indicates a continuous belt, preferably of a textile material, which extends around the rear side of roller C, from the top thereof to the upper side of roller F, around the front 60 and bottom of the latter, and up over the upper side of roller E, and back to the lower side of roller C, as shown in Figs. 2 and 3, the roller E revolving in a direction contrary to the rollers C and F. The roller C is larger 65 than the other rolls, E F, and extends downward into the adhesive material in the box B, so that as the belt G passes around the roll C it is immersed in and coated with the solution in the box. 70

In order that the paste or other substance may be spread evenly over the belt, we attach a scraper, H, to the rear side of the box B, the upper end of the scraper H being curved, and its edge bearing on the belt being 75 notched or serrated, as shown, so as not to remove all of the paste.

I indicates a shaft or holder journaled in the rear end of the uprights $a-a$, and on which is wound the strip, J, of paper containing the 80 printed addresses, the said shaft being retained in place by hooks c in the same manner as the roll C. The uprights are slotted to allow the ready removal of the shaft I, and the latter is provided with a winch or handle, 85 d , by which to wind up the paper.

At the front end of the machine, on the inner faces of the uprights $a-a$, are vertical blocks or guides K, which are securely fastened to the uprights and connected by means of a plate 90 or bar, d , as shown in Figs. 2, 3, and 4, each of said guides or blocks K being provided with a vertical slot or groove, e , as also shown in said figures.

Sliding vertically in the slots or grooves e is 95 the plunger L, said plunger carrying the cut-

ting-bar or knife M and the mechanism, hereinafter to be described, for causing the feed of the strip J.

A handle, N, by which to depress the plunger L, is secured to the upper edge thereof, as shown in Figs. 1 and 3, said handle N being provided with a rearwardly-extending arm, f, through which passes the upper end of a vertical rod, g. The lower end of rod g is secured 10 to a bracket or arm, h, rigidly secured to the rear side of plate or bar d, as shown in Fig. 3, the said rod or stem g being encircled by a spiral spring, i, which bears at one end upon the bracket h, and at the other end beneath the 15 arm f. The arm f is slotted and made adjustable upon the handle L, in order to vary the compression and consequent action of the spring i.

The lower ends of the guides or blocks K are 20 connected by a plate or bar, j, to which is secured the stationary cutter k, as shown in Figs. 3 and 4. The forward edge of the cutter k is on a line with the rear edge of the movable or reciprocating cutter M, thus insuring a shearing action of the cutters.

Extending transversely across the front lower edge of the plunger L, and secured thereto by screws l, is a plate, m, which extends out beyond the sides of the plunger and bears against 30 the front faces of the blocks or guides K, thus serving to steady the plunger L in its movements. The screws l serve also to secure the cutter M to the plunger.

One end of the plate m is provided with an 35 upright arm, n, which inclines slightly to the rear of the machine, said arm n being preferably cylindrical in cross-section, and of a length greater than the movement of the plunger. The rod or bar n is encircled by the 40 forward end of a bar or rod, o, guided by brackets p, secured to the side of the frame, the vertical movement of the plunger L and the rod or bar n causing the reciprocation of the bar or rod o through its guides p.

To the rear end of the rod o is pivoted a 45 shorter arm, o', carrying an adjustable pawl, q, this rearward extension o' extending over the ratchet-wheel D on shaft or journal b.

When the rod o is moved backward, the pawl 50 q near the end thereof engages with the ratchet-wheel D and turns the latter in a forward direction. As the rod o' moves backward preparatory to engaging with the wheel D its rear end strikes and rides upon the upper 55 face of an adjustable bracket, r, secured to the frame a by a set-screw, s, as shown in Figs. 1, 4, and 5, the bracket r being provided with a slot, through which the screw s is passed. When the bracket r is at its highest position, the 60 rear end of the lever or rod o' can drop a short distance only, and the result is, that its pawl q will engage with the first or second tooth of the wheel D in rear of the tooth previously engaged. Should, however, the addresses be 65 wider, it will only be necessary to lower the bracket r, which would allow the arm o' to

drop lower than under the preceding adjustment, and engage with a tooth of the wheel D several teeth distant from the tooth last engaged, and thus move the wheel D and strip 70 J a greater distance.

A roller, u, extends transversely across the machine immediately in front of the roller F, in order to cause the paper to feed out properly between the cutters.

The lower forward end of each of the side frames or uprights, a, is cut away in order to form room for the paper or other article to be addressed.

The operation of the machine is as follows: 80 The printed address strip J is wound upon the roller I and its end passed over the guide or scraper H onto the belt G, and as said belt G is covered with paste or other adhesive substance the strip J is carried forward 85 thereby. The downward movement of the plunger L causes the reciprocation of the rod o' through the medium of rod m. As the plunger is caused to rise (by the spring i) the rod n causes the forward movement of the 90 rod o' and the consequent rotation of the rollers C E F through the medium of the pawl q and ratchet-wheel D. This operation is repeated until the paper strip J is fed forward on the belt G to the roller u and leaves 95 the belt and passes between over the upper face of the cutter k. Another descent of the plunger severs the desired address from the printed strip and presses the same firmly against the package to be addressed, which 100 has in the meantime been placed immediately under the plunger. At the next movement of the plunger it rotates the feed-belt G and brings the next address in position to be cut off and attached. It will be seen that as the 105 paper strip J is fed forward by the belt G its under surface will be evenly coated with the adhesive material used.

Having thus described our invention, what 110 we claim is—

1. The herein-described addressing-machine, 115 consisting of a frame, paste box or receptacle B, rolls C E F, endless belt G, paper-feed roll I, plunger L, carrying cutter M and arm n, stationary cutter k, ratchet-wheel D, and arm o, provided with pawl q, all substantially as shown and described.

2. In an addressing-machine, the combination of a frame, box B, roll C, belt G, carried thereby, roll I, and the combined guide and 120 scraper H, secured to the rear side of the box B, as and for the purpose set forth.

3. In an addressing-machine, the combination of a frame, blocks K, bar d, connecting the latter and provided with arm h and rod g, 125 and plunger L, moving in the blocks K, and provided with arms f, and a spring, i, between the arms f h, as and for the purpose set forth.

4. In an addressing-machine, the combination of a frame, rolls C F, the former provided with ratchet-wheel D, belt G, carried by said 130

rolls, plunger L, having inclined rod n, reciprocating rod o, encircling and moved by rod n, and provided with pawl q, as and for the purpose set forth.

5. In an addressing-machine, the combination of a frame, a feeding device with a ratchet-wheel, a plunger, a reciprocating rod moved by said plunger and having a pivoted tail or extension provided with a pawl, and

an adjustable bracket secured upon the frame to and adapted to vary the movement or action of the pawl.
